UNITED STATES PATENT OFFICE

LYMAN C. HUFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

PROTECTIVE LINING FOR VESSELS

Application filed December 1, 1930. Serial No. 499,296. 72-14

This invention relates to protective linings for vessels, and relates more particularly to an improved method and means for supporting and reinforcing linings which may be applied to the interior of a vessel while in their plastic state.

My improved form of lining may be employed to protect the surfaces of any vessel, and may be especially adapted for use in protecting the metallic walls of vessels exposed to the corrosive effects of high temperatures and pressures, or other destructive action tending to shorten the life of a vessel.

Primarily, the invention comprises mounting upon the walls of a vessel to be protected, by welding or other well-known means, a woven wire mesh, the strands of which may be crimped or bent from the planes of the interwoven strands to effect a finished mesh having a depth or thickness substantially greater than twice the diameter or gauge of said wire strands, adapted to reinforce and support a layer of plastic protective material to be applied over said mesh and upon the interior walls of said vessel, said plastic layer being of such proportion or thickness as to substantially cover and imbed said wire mesh.

Any well-known composition of protective coating may be used, such as, for example, a plastic material comprising crushed firebrick or gannister, sand and Portland cement, or other suitable binding material, admixed with water. The mixture may be applied in its plastic state to the interior walls of a chamber employed in an oil cracking process through means of a troweling action, cement gun, or any other desired means.

Another form of plastic lining which may be adopted, may comprise a mixture of high-temperature furnace cement, sodium silicate, sand and asbestos fibre, which may be sprayed upon the walls of the vessel with a furnace cement gun or other well-known means. Such plastic protective linings may be cured and hardened by suitable methods, such as passing hot flue gases through the vessel, or by the application of external heat thereto.

One difficulty encountered with linings of this nature has been their tendency to spall away from the walls of a vessel, leaving an

exposed, unprotected surface underneath. Reinforcement of said lining by any ordinary means, such as, for example, interposing a flat wire mesh, expanded metal (commonly termed "metal lath"), or the like, within the material comprising the lining has resulted in a separation of the lining into layers, rather than serving as a means for supporting and reinforcing it. Spalling, apparently, is intensified by this interpositioning, especially from the outer exposed surface of the liner to the flat wire mesh or other means employed, while that portion of the liner retained beneath the reinforcing means becomes loose and of little or no protective value.

I have found that by the use of the reinforcing means of the present invention, a lining bound together in a more homogeneous and monolithic mass, with a consequent substantial prevention of spalling and a resultant increased and prolonged life may be obtained.

Further objects and advantages of the invention will be apparent from the following description and attached diagrammatic drawing, in which,

Fig. 1 is a fragmentary view, showing a portion of the length and breadth of a wire mesh which may be employed;

Fig. 2 is a sectional view, taken on a line 2-2 of Fig. 1; and

Fig. 3 is a sectional view, showing a form of the invention as it may be applied in one instance.

Referring to the drawing, strands of wire 1, of any desired gauge, may be interwoven, as at 2, to form a wire mesh of any desired dimension. That portion of the strands of wire 1 between said interwoven points 2 may be crimped or bent alternately in an inward and outward direction from the plane of said points 2 to substantially a point 3, in order to provide a mesh with a depth substantially greater than twice the diameter of said strands of wire 1. In this form, the wire mesh may be suitably mounted upon the inner surfaces of a chamber 4 by spot welding, or by other well-known means, as illustrated at 6. After said mesh has been suitably mounted upon the inner surfaces of said

chamber, a protective lining for the inner surfaces of said chamber to a depth to about the extent of a line 7, of Fig. 2, may be applied thereover. Said protective lining may 5 comprise a plastic coating 8, applied as hereinbefore described over said wire mesh. As will be clearly seen from Fig. 3, the strands of wire 1, bent alternately inwardly and outwardly from the plane of said interwoven 10 points 2, to said points 3, will afford a greater reinforcement for said protective lining, binding and holding the same throughout substantially its entire depth, as illustrated in said Fig. 3 at the points 9.

15 It is to be understood that I have for purposes of illustration only shown one form of wire mesh which may be adapted to reinforce a plastic lining applied thereover. Obviously, other forms of wire mesh may be employed, and which may be adapted to produce the permeating effect which the invention affords.

I claim as my invention:—

1. In combination, a chamber having a 25 granular heat-resistant lining on an inner wall thereof, and reinforcing means for said lining, comprising a crimped wire mesh, the crests and troughs of said crimps lying in parallel planes and spaced a greater distance 20 from each other than twice the diameter of said wire.

2. In combination, a vessel having a granular heat-resistant lining on an inner wall thereof, and reinforcing means for said lining comprising in combination a wire mesh 35 interwoven in a common plane, the unwoven strands of said mesh being crimped and spaced in an inward and outward direction from said interwoven plane a distance equal 40 to the depth of one crimp.

3. In combination, a vessel having a granular heat-resistant lining on an inner wall thereof, and reinforcing means for said lining comprising in combination a wire mesh 45 interwoven in a common plane, the unwoven strands of said mesh being crimped in an alternate inward and outward direction from each interwoven plane to an extent at least substantially twice the diameter of the wire 50 strands comprising said mesh.

4. In combination, a vessel having a granular heat-resistant lining on an inner wall thereof, and reinforcing means for said lining comprising in combination a cementitious 55 material having imbedded therein a wire mesh, the strands comprising said mesh being crimped so that the crests of said crimped strands are spaced from the troughs of said crimps in a plane parallel to the plane of the 60 mesh, a distance greater than twice the diameter of the strands comprising said mesh.

In testimony whereof I affix my signature.

LYMAN C. HUFF.
